UNITED STATES PATENT OFFICE.

FRANK HAGEN, OF BREESE, ILLINOIS.

COMBINED MATCH-BOX, CIGAR-REST, AND ASH-TRAY.

Specification of Letters Patent.

Patented Apr. 27, 1915.

1,137,481.

Application filed February 16, 1914. Serial No. 819,008.

To all whom it may concern:

Be it known that I, FRANK HAGEN, a citizen of the United States, residing at Breese, in the county of Clinton and State of Illinois, have invented certain new and useful 5 Improvements in Combined Match-Boxes, Cigar-Rests, and Ash-Trays, of which the following is a specification, reference being had to the accompanying drawings.

10 This invention relates to new and useful improvements in combined match receptacles, cigar rests and ash trays and the primary object of the invention is to provide a combined device of this character which is 15 extremely simple in construction and one which will effectively carry out all of the purposes for which the same is designed.

15 A further object of the invention resides in providing an improved device which is 20 inexpensive to manufacture and one which will be very useful in practice.

With these and other objects in view, the invention consists in the novel features of construction, combination and arrangement 25 of parts as will be hereinafter referred to and more particularly pointed out in the specification and claim.

30 In the accompanying drawing forming a part of this application, Figure 1 is a perspective view of a device showing the cigar rest disposed to its operative position. Fig. 2 is a vertical longitudinal section through the device. Fig. 3 is a vertical transverse section therethrough.

35 In describing my invention, I shall refer to the drawing in which similar reference characters designate corresponding parts throughout the several views and in which—

1 indicates a casing formed of metal of 40 any desired character whatsoever, said casing being of rectangular design having a top wall 2, a bottom wall 3 and side walls 4. This casing is of such design as to readily receive in one end thereof, a match box 5, 45 the latter being of the type used for the well known safety matches and one of the side walls 4 has a portion cut therefrom, as shown at 6, whereby the material in the side of the match box for striking the matches may be 50 engaged from the outside of the casing 1.

The end of the casing 1 which is designed for the receiving therein of the box 5, may be called the box receiving end of the casing and as stated, this casing is designed to 55 snugly receive this box therein. In order to permit this device to be used as an adver-

tising novelty, a portion is cut from the bottom wall 3 thereof to permit any advertising matter contained on the cover of the match box 5 to be readily disposed therethrough. 60 While the match box 5 is snugly received between the walls of the casing 1, at the box receiving end thereof, it is also desirable to prevent any possibility of the box dropping from the casing from any cause whatsoever 65 and, to this end, the side edges of the opening formed by the cutting away of the bottom, are deflected, as shown at 8, whereby to bind tightly against one face of the cover of the box 5. It is obvious from this construction that when the match box is inserted in the casing, the same is readily held in place until removed by hand.

The interior of the casing 1 is divided into compartments through the provision of a division wall 9 therein. The one compartment receives the box 5 therein, while the other compartment, indicated as 10, forms a compartment for the reception of ashes, as will be hereinafter and more particularly set 80 forth. In carrying out this idea, the top wall 2 is cut away over this compartment 10, as indicated at 11, the cut away portion terminating at a point adjacent the one end of the top wall. This compartment 10 forms 85 an ash tray as stated and the ashes from the lighted cigar or cigarette may be readily removed therefrom by striking the cigar or cigarette against the portions of the top surrounding the opening or cut away portion 11 90 therein. It must be here stated that the division wall 9 is partially held in place by means of a depending flange 12 formed on the top wall 2 at the edge of the opening 11 95 therein. This division wall is, of course, 95 held in place by any preferred means but this depending flange forms a stop or the like against which said wall may contact.

Hinged to the top wall 2, at the edge of the opening 11 thereof, is a covering plate 100 13 which, when in its lowered position, covers the opening 11 in the top wall. The outer edge of this covering plate is provided with a depending flange 14 forming a finger piece whereby said covering plate may be 105 raised and lowered readily when desired. This covering plate is primarily provided for the purpose of providing the cigar rest and, to this end, a rest 15 is secured in place on the under face of the covering plate 13. 110 When the covering plate is turned to its open position to rest on the upper face of the

top wall 2, said rest 15 is in its operative position so as to receive a cigar or cigarette therein. However, when the plate 13 is lowered over the opening 11 in the top wall, 5 said rest is in its inoperative position. The compartment 10 forming the ash tray, having an open end, admits of the ashes or other trash received therein to be readily emptied therefrom.

10 From the foregoing description of the construction of my improved device, the manner of applying the same to use will be readily understood and it will be seen that I have provided an improved combined device which will be extremely efficient in carrying out all the purposes for which the same is designed. It will further be seen that the device is simple and durable in construction and one which will be very useful 15 in practice.

While I have particularly described the elements best adapted to perform the functions set forth, it is obvious that various changes in form, proportion and in the 20 minor details of construction may be resorted to without departing from the spirit

or sacrificing any of the principles of the invention.

Having thus described this invention, what I claim is:

30 A device of the class described including a rectangular casing, the opposite ends whereof being open, a partition within the casing dividing the same into two compartments, a box slidably arranged within one 35 of the compartments, the top of the casing over the remaining compartment being cut out, a plate hingedly connected to the top of the casing adjacent the inner end of the cut out portion and normally closing said 40 compartment, the outer extremity of the plate being angularly disposed to partially overlie the adjacent open end of the casing, and a cigar rest mounted upon the inner face of said plate.

45 In testimony whereof I hereunto affix my signature in the presence of two witnesses.

FRANK HAGEN.
